(57) **CLAIM**

The ornamental design for a candle glass container, as shown and described.

DESCRIPTION

FIG. 1 is a top perspective view of the candle glass container for the present invention, showing our new design, with the phantom lines depicting solely environmental structure and forming no part of the claimed design;

FIG. 2 is a side elevational view thereof;

FIG. 3 is a top plan view thereof; and,

FIG. 4 is a bottom plan view thereof.
